GUITAR HEAD

Robert Podall, Chicago, Ill., assignor to Kay Musical
Instrument Co., a corporation of Illinois
Filed Aug. 23, 1965, Ser. No. 86,682

Term of patent 14 years

(Cl. D56—1)

The dominant features of my new design are shown in solid lines in the drawing.

I claim:

The ornamental design for a guitar head, substantially as shown and described.
